GROUND ANCHOR

Merton L. Clevett, Jr., East Natick, Mass.

Application December 24, 1954, Serial No. 477,501

3 Claims. (Cl. 189—90)

This invention relates to ground anchors and more particularly to ground anchors which may be placed in position without digging a preliminary hole in the earth.

In designing and developing ground anchors for numerous industrial uses, a number of specific problems are presented. In the first place, in order to obtain the maximum anchoring effect, it is important to locate a wide, substantially flat plate or flange beneath the surface of the earth and to provide a substantially firm and durable connection to such plate in a direction normal to the plane of the plate. Thereafter guy wires, tent ropes, antenna mast stays, telephone pole stays and the like may be secured to the connection and the anchor will provide a resistance to the thrust of such guy wires in the direction of the connecting members which will be proportional to the size of the plate, and the weight and rigidity of the earth which lies between the plate and the surface of the earth. Thus it is important to locate the anchor plate in the ground with the least disturbance to the earth around it in order to obtain the full benefit of the rigidity of the earth in its natural state. For this reason ground anchors which require a large hole to be dug in the direction of the thrust, so that an anchor can be placed down in the hole, which is thereafter filled in with earth, have the disadvantage that the earth along the axis of the thrust has been disturbed and has much less resistance than substantially undisturbed earth.

One form of ground anchor in the past has entailed digging a hole at right angles to the direction of the expected thrust, placing the plate in the hole, and thereafter driving an anchor connecting rod through the earth from the side of the expected direction of thrust and towards the foot of the hole. With such a device the connecting rod must be driven in accurately so that it will eventually strike the plate lying at the bottom of the hole. Thereafter the rod and plate are joined by means of a threaded connection which is engaged by twisting the rod. This latter mentioned anchor is satisfactory from the standpoint of holding power but the threaded connection is very difficult to fit when the plate is at the bottom of the hole and must be fitted to the rod while it remains penetrating through several feet of earth, and also it is a decided inconvenience to have to dig the hole and thereafter obtain an accurate registration between the said threaded elements. Other types of conventional anchors involve complicated spreading elements which expand after the anchor has been driven into the ground, and are unsatisfactory either because they are highly complicated and expensive, or else they also require substantially large holes to be dug which result in added expense and in many cases they are not sufficiently durable.

Therefore, it is an object of my invention to provide a ground anchor which can be inserted into the earth along the axis of thrust without the necessity of digging a hole. A further object of my invention is the provision of such an anchor in which the connection between the anchor plate and the guy, stay or rope permits the anchor

2

plate to assume a position normal to the thrust and which is extremely firm and durable.

In the accomplishment of these and other objects of my invention in a preferred embodiment thereof, I employ a triangular-shaped base plate having a lower portion tapered to provide easy penetration into the ground and an upper portion which is flared laterally to either side to provide a substantially broad anchoring surface. Approximately in the center of the base plate, I connect an anchor rod or other thrust bearing element by means of a joint which permits the base plate to pivot relative to the rod. Also on one side of the base plate extending upwardly from the pivotal connection of said rod, I provide a recess to receive the anchor rod when it is pivoted to a plane substantially parallel to the base plate. Thus when an anchor rod is in the recess, the ground anchor is in a position to be driven into the ground. When the rod and base plate are in this relatively parallel position, it is important that they remain so throughout the driving operation, which may be accomplished by the anchor rod itself or by a separate driving tool. If the plate does not remain parallel, it may veer off to one side or the other giving it an improper position or even preventing the base plate from being driven into the ground at all. Thus in order to hold the rod and plate parallel, it is a feature of my invention that I provide means associated with the driving element and the base plate for holding the rod and base plate roughly parallel during the driving operation.

A further feature of my invention is the provision of means for easy penetration of the anchor into the earth, and for causing the anchor base plate to pivot to a plane normal to the direction of thrust when the rod or thrust bearing element is subjected to operating tension.

Further objects and features of my invention will best be understood and appreciated from the following detailed description of a preferred embodiment thereof, selected for purposes of illustration and shown in the accompanying drawings in which:

Fig. 1 is a view in perspective of the ground anchor of my invention diagrammatically shown in its anchoring position under the surface of the earth;

Fig. 2 is a view in front elevation of the rod and base plate in parallel relation;

Fig. 3 is a view in cross section along the lines 3—3 of Fig. 2;

Fig. 4 is a view similar to Fig. 3 except the anchor rod is in an elevated position;

Fig. 5 is a view in rear elevation;

Fig. 6 is a plan view looking axially along the anchor rod with the base plate in parallel relation to the anchor rod;

Fig. 7 is a view in front elevation of a variation of the ground anchor of my invention;

Fig. 8 is a view in cross section along the lines 8—8 of Fig. 7;

Fig. 9 is a view in cross section showing the embodiment of Figs. 1—6 in the anchored position;

Fig. 10 is a view in cross section showing the embodiment of Figs. 7 and 8 in the anchored position;

Fig. 11 is a plan view of a further variation of the ground anchor of my invention;

Fig. 12 is a view in cross section along the lines 12—12 of Fig. 11;

Fig. 13 is a view in front elevation of still a further variation of the ground anchor of my invention;

Fig. 14 is a view in cross section along the lines 14—14 of Fig. 13;

Fig. 15 is a plan view of the anchor plate of the embodiment shown in Fig. 13;

Fig. 16 is a view in rear elevation of the embodiment shown in Fig. 13; and

Fig. 17 is a cross sectional view along the lines 14—14 of Fig. 13 except that the ground plate is in a horizontal position and the connecting member is standing in a plane normal to the ground.

The preferred embodiment of my invention herein shown includes a triangular-shaped base plate 10 and an anchor rod 12 pivotally connected by a ball and socket arrangement having a ball 14 mounted on the rod 12 and a socket 16 in the back side of the plate 10. The plate 10 may preferably be of cast metal, such as cast iron, cast aluminum alloys, or the like, and the rod 12 may be fabricated from conventional steel rod.

The front face of the plate 10 is provided with an elongated recess 18 to receive the rod 12 when the rod is pivoted around to a position parallel to the plane of the base plate 10, and when the rod is in this position relative to the base plate 10, the ground anchor is ready to be driven into the ground. However, in order to hold the ground anchor in that position relative to the rod, I provide a flange in the form of a nut 20 located on the rod upward from the ball 14 and roughly adjacent to the upper margin of the base plate 10. The nut 20 is adapted to seat into a socket 22 in the upper portion of the base plate 10 when the anchor is being driven into the ground but to pull out of the socket 22 when the rod is pulled upwardly after the anchor has been fully driven home. In order to accomplish this, the socket 16 on the back side of the plate 10 is elongated, thus permitting the ball 14 to move relative to the plate 10 when it is withdrawn. It will be seen with reference to Fig. 4 that when the ball 14 is pulled upwardly to its uppermost extremity in the socket 16 that the nut 20 clears the top edge of the socket 22 thus permitting the anchor to tip relative to the rod 12. After the anchor has been driven in to the desired position, the rod 12 is simply withdrawn a short distance and the base plate 10 tips and assumes a position roughly normal to the axis of the rod 12, thereafter substantially resisting any further withdrawing force by forces proportional to the stiffness of the earth, the weight of the material on top of the anchor, and the size of the base plate 10. In order to assist the tipping motion of the plate 10 when a desired position has been reached, I recess the base plate 10 on one side at 24 so that the principal resistance of the withdrawing motion tends more normally to tilt the base plate 10 to its final position substantially normal to the rod 10.

In a second embodiment of my invention shown in Figs. 7, 8 and 10, I employ a base plate 26 and rod 28. The plate 26 and rod 28 are connected likewise by a ball element 30 and a socket 32, but it will be noted that the shank of the rod 28 is not threaded and has no nut 20 and that the socket 32 is not elongated as was the socket 16. However, the face of the base plate 26 is provided with an elongated recess 34 which is in all respects similar to the recess 18. The embodiment of Figs. 7 and 8, however, is maintained parallel to the rod 28 during the driving phase of the operation by means of a slight lateral flare 36 on the rear face of the base plate 26. The flare 36 serves to drive the rear side of the upper portion of the base plate 26 towards the rod 28 and thus maintain the parallel alignment between these two elements. When the anchor reaches the desired position, the rod 28 is pulled back and as it recedes the plate 26 tips relative thereto until it reaches a position substantially normal to the direction of thrust which is the position of maximum anchoring effect. It should be noted that the flare 36 serves to assist this pivotal action of the anchor in the ground after the anchor has been driven in as well as holding the anchor straight during the driving operation. It should also be noted that there is no axial relative motion between the rod 28 and the plate 26 as there was between the rod 12 and plate 10 previously described. Thus random particles of dirt cannot accidentally interfere with the operation of the device of Figs. 7, 8 and

10 as might be the case with the device of Figs. 16 and 9. If the ball joints previously described are not sufficiently strong, additional strength may be obtained by providing trunnions 37 to each side of the ball 30, and widening the socket 32 accordingly as may seen in Figs. 11 and 12.

In the embodiments of my invention shown in Figs. 1-12 the ground anchor is driven into the ground by means of hammer blows applied directly to the upper end of the connecting rod and while this may be convenient and desirable, especially in the larger sizes, the connecting rod may not be sufficiently rigid in the smaller sizes to take the impact which may be necessary to drive the ground anchor into the earth. Thus in the smaller sizes a lighter connecting rod may be employed or even wire, cable or the like. A mechanism for such a connection employing the essential features of my invention is shown in Figs. 13-17. In this embodiment of my invention a base plate 44 is employed having a tapered lower end in a manner similar to the previously described embodiments. However, the base plate 44 is provided with an outwardly extending flare at 46 to prepare a path for penetration of the connecting elements of the ground plate into the ground. The base plate 44 is provided with a recess 48 in its upper portion which is substantially similar to the recesses 18 and 34 hitherto described. However, the recess 48 is slightly narrowed adjacent to its opening as indicated at 50. The purpose for narrowing the recess 48 at 50 is to accommodate a driving tool indicated at 52 in Fig. 14 such that a downwardly extending lug 54 on the driving tool 52 can enter the recess 48 in a relatively snug fit, and thereafter hold the base plate 44 roughly parallel to the driving tool 52. The thrust of the driving tool 52 is taken by an annular flange 56 which rests on the upper butt edge of the base plate 44.

In this embodiment the connecting elements for the guy wires to the base plate 44 is a rod 58 which is pivotally connected to the base plate 44 by means of a ball and pin connection 60 similar to that shown in Figs. 11 and 12. The rod 58 is bent slightly so that its contour adjacent to the lower end of the driving tool 54 will conform more accurately to the path the ground anchor takes through the earth. The upper portion of the rod 58 is provided with a rounded hole 62 adapted to receive guy wire, cable, or the like. The rod 58 may be very short as shown or it may be long enough to extend upward to the surface of the earth. With reference to Fig. 17 it will be seen that the rod 58 in the operative position does not stand up perfectly vertically, but it will be understood that the slight bend in the rod 58 is of no consequence and was merely for the purpose of easy entrance into the ground as was previously explained. In operation, this slight bend may even straighten out.

It will now be seen that the ground anchor of my invention is particularly durable and adapts itself readily to use in a wide variety of terrains and applications. It will also be noted that the point of thrust from the connecting element to the various base plates is approximately at the geometric center of the base plate in a plane normal to the direction of thrust when the plate is in the anchoring position shown in Figs. 9, 10 and 17. Thus the ground anchor will tend always to remain in a normal position such that unexpected shocks or loads, or the like will not tend to tip the ground anchor and cause it to pull out of the ground in any fashion other than in a plane normal to the direction of thrust, in which plane it has the maximum resistance. On the other hand in the embodiments shown in Figs. 7, 8 and 10-12, when the plate is parallel to the rod for driving the anchor into the ground, the point of thrust of the rod lies to the front of the line of the geometric center of resistance of the plate as is shown by the dotted line in Fig. 12. This fact serves to keep the plate parallel to the

rod while driving the anchor into the ground, and also serves to tip it normal to the rod when assuming the anchoring position.

Certain minor variations of this preferred embodiment of my invention will now be apparent to those skilled in the art, and therefore, it is not intended to confine the invention to the precise form herein shown, but rather to limit it in terms of the appended claims.

Having thus described and disclosed preferred embodiments of my invention, what I claim as new and desire to secure by Letters Patent of the United States is:

1. A ground anchor comprising a shaft with a head at one end and a peripheral flange spaced from said head, a base plate with a tapered end, a front face, a back face, and a rear end face, said plate having a hole running from its front face to its back face, said hole being larger than the cross-section of said shaft but smaller than said flange and head, said shaft loosely extending through said hole with said head located on the rear side of said plate and said flange located on the front side of said plate, said front face having an elongated slot running from said hole back to said rear end to receive said shaft when said shaft is pivoted into parallel relation with the plane of said plate, said back face having a cavity communicating with said hole for receiving said head, said cavity being sufficiently large to permit limited relative reciprocal movement of said head between a first position furthest from said tapered end and a second position closest to said tapered end, when said shaft is disposed in said slot in parallel relation to the plane of said plate, and means at said rear end for cooperating with said flange to lock said shaft in said parallel position only when said head is in said second position.

2. A ground anchor comprising an anchor rod with an enlarged head at one end and a peripheral flange spaced from said head, a base plate having a tapered bottom end, a front face, a rear face, and a top end face opposite said tapered end, said front face having a longitudinally extending slot running from said end face and terminating at the substantially geometric center of said base plate, said rear face having a cavity at said geometric center, said cavity and said slot overlapping to form an open passageway between said rear and front faces, said rod loosely extending through said passageway with said head disposed on the rear side of said plate and said flange disposed on the front side of said plate, said passageway having a diameter smaller than said head and said flange whereby said head and flange are prevented from passing therethrough, said cavity having a longitudinal dimension measured on a line running

from said top end face to said tapered end sufficient to permit limited relative reciprocal movement of said head toward and away from said tapered end when said shaft is resting in said slot with its head disposed in said cavity, and means provided at said end surface for lockingly engaging said flange to prevent relative pivotal movement of said shaft out of said slot when said head is urged forward toward said tapered end.

3. A ground anchor comprising, an anchor rod and a base plate pivotally connected to said rod by a ball and socket connection, said anchor rod having a ball at one end and a peripheral flange spaced from said ball, said base plate comprising a tapered end, a front face, a back face, and an end face opposite to said tapered end, 10 said plate having a socket in said back face for said ball, said socket being sufficiently large to permit movement of said ball toward and away from said tapered end between a first position nearest said end face and a second position nearest said tapered end, said rod extending through said plate outwardly of said front face, 15 said front face further being provided with an elongated recess for receiving said rod when said rod is pivoted toward said end face into the plane of said plate, said recess extending from said end face toward said tapered end and terminating in overlapping communicating relation with said socket, said plate also having an end socket for said flange formed in said end face, said end socket opening into said front face and forming in part 20 a continuation of said recess, whereby to receive said rod when it is pivoted into the plane of said plate to place said flange in seating alinement with said end socket, said flange being seated in said socket and locking said rod against pivotal movement when with said rod disposed in the plane of said plate said ball is in said 25 second position, said rod with said ball in said first position being free to pivot out of the plane of said plate.
